UNITED STATES PATENT OFFICE

108,629

DESIGN FOR A DISPENSER CABINET

Tully De Stefani, Chicago, Ill., assignor to The
Liquid Carbonic Corporation, Chicago, Ill., a
corporation of Delaware

Application January 12, 1938, Serial No. 74,217

Term of patent 14 years

To all whom it may concern:

Be it known that I, Tully De Stefani, a citizen of the United States and a resident of Chicago, in the county of Cook and State of Illinois, have invented a new, original, and ornamental Design for a Dispenser Cabinet, of which the following is a specification, reference being had to the accompanying drawing forming a part thereof, and in which:

Fig. 1 is a front perspective view of a dispenser

cabinet, showing my new design, the left side thereof being similar to the showing of the right; and

Fig. 2 is a top plan view of the dispenser cabinet shown in Fig. 1, at a reduced scale with respect thereto.

I claim:

The ornamental design for a dispenser cabinet, as shown and described.

TULLY DE STEFANI.
